US00D910619S

(12) **United States Design Patent** (10) **Patent No.:** **US D910,619 S**
(45) **Date of Patent:** **** Feb. 16, 2021**

(54) **DISPLAY DEVICE**

(71) Applicant: **Samsung Electronics Co., Ltd.**, Suwon-si (KR)

(72) Inventor: **Seokjin Lim**, Suwon-si (KR)

(73) Assignee: **Samsung Electronics Co., Ltd.**, Suwon-si (KR)

(**) Term: **15 Years**

(21) Appl. No.: **29/689,491**

(22) Filed: **Apr. 30, 2019**

(30) **Foreign Application Priority Data**

Nov. 23, 2018 (KR) 30-2018-0054618

(51) **LOC (13) Cl.** **14-02**

(52) **U.S. Cl.**

USPC **D14/345**; D14/341

(57) **CLAIM**

I claim the ornamental design for a display device, as shown and described.

DESCRIPTION

FIG. 1 is a front perspective view of a display device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a display device showing my new design in which the display device is shown in an open position;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a rear perspective view thereof.

The broken lines in the figures depict portions of the display device which form no part of the claimed design.
